UNITED STATES PATENT OFFICE.

LOUIS PRIEST, OF FLINT, MICHIGAN.

VEHICLE-BODY.

SPECIFICATION forming part of Letters Patent No. 733,676, dated July 14, 1903.

Application filed April 7, 1902. Serial No. 101,713. (No model.)

To all whom it may concern:

Be it known that I, LOUIS PRIEST, a citizen of the United States, residing at Flint, in the county of Genesee and State of Michigan, 5 have invented a new and useful Vehicle-Body, of which the following is a specification.

The present invention relates to vehicle-bodies; and the object thereof is to provide a structure which is much cheaper than that 10 ordinarily employed and at the same time is without the objectionable features of the same.

In the usual construction the side walls or 15 panels are made of wood, and it is practically impossible to prevent their warping and checking or cracking when they are subjected to the extremes of temperature. Then, again, it has been the custom to employ screws in 20 the construction, which screws are counter-sunk and afterward covered by wooden plugs that are dipped in glue and driven into the openings over the screw-heads. Manufacturers have great difficulty with these plugs, as they very often shrink and drop out or 25 crack the finish around the opening, thereby necessitating the refinishing of the body. Furthermore, considerable trouble is experienced in preventing the corners cracking, due to the expansion and contraction of the wood.

30 It is the aim of this invention to provide a structure in which all the objections above noted are eliminated, said structure being very cheap and not requiring expensive machinery in the manufacture thereof.

35 The preferred embodiment of this invention is fully illustrated in the accompanying drawings, wherein—

Figure 1 is a perspective view of a vehicle-body constructed in accordance with the 40 present invention. Fig. 2 is a vertical sectional view through the same. Fig. 3 is a detail horizontal sectional view through one of the corners. Fig. 4 is a detail perspective view of one of the corners, showing the shield removed therefrom. Fig. 5 is a perspective view 45 of said shield. Fig. 6 is a vertical sectional view, on an enlarged scale, more clearly showing the construction of the walls and the means for securing the cap-strip in place 50 thereon. Fig. 7 is a detail perspective view of one of the eyelets employed.

Similar numerals of reference designate cor-

responding parts in all the figures of the drawings.

In the construction of the invention a suitable frame is employed, preferably consisting of side and end sills 10 and 11, corner-posts 12, and upright seat-posts 13, to the upper ends of which are secured rack-bars 14, that support the seat. Only the skeleton of the 60 seat is shown, and this skeleton comprises seat frame-bars 15, back frame-bars 16, including a center-brace 17, and a spring-supporting bar 18.

The important feature to be observed in 65 this invention is the construction of the walls of the body and seat and the manner of securing the same to the frame. These walls each comprise an intermediate upright core-plate 19, preferably of wood, and outer and 70 inner sheathings 20, preferably of paper or similar fibrous material. These three elements or members are glued securely together, so as to practically form a solid wall. Their upper edges are protected from wear 75 and from the elements by means of a cap-strip 21, preferably of metal and bowed in the manner shown in Figs. 2 and 6. This cap-plate overlaps the upper edge of the wall and is secured in place by having indented 80 portions 22, that engage in the outer faces of the sheathings and securely hold said strip against accidental displacement. At the corners the outer sheathings are cut away, as shown, and the outer face of the core is cov- 85 ered with a fabric 23, that may be of canvas, wire-netting, or the like, said canvas joining the meeting ends of the adjacent walls, and thus securely fastening the joint against opening. Eyelets 24 are secured to the outer 90 face of the core. As shown in Fig. 4, said eyelets comprise body-plates having spurs 25, which are embedded in the core, and through these eyelets are passed fastening devices 26, in the form of screws, that engage in the cor- 95 ner-posts 12. The corner-posts are prefer- ably braced by means of curved braces 27, secured to their upper ends and to the side walls or other portions of the body-frame. The fabric 23 and the fastening devices are 100 covered by a corner-shield 28, formed of a single piece of cardboard or paper and of the proper shape to fit in the cut-out portions of the wall, being secured in place by glue or

other fastening means. The side and rear walls of the seat are constructed in substantially the same manner as that of the body, said walls being secured to the frame in the 5 manner shown, so that they will not interfere with the upholstering of the seat.

The advantages for this construction will be perfectly apparent. In the first place the body-walls are of very inexpensive material, 10 as the paper may be made in proper shape before application, so that there need be little waste of this material, and the intermediate core-plate can be made of inexpensive lumber. At the same time the cap-strip protects 15 the wall from wear and from the action of the elements. There can be no cracking or checking at the corners, as the joint is secured together by the fabric and the outer surface is continuous at the corner, being 20 made so by the sheathing, which also covers the fastening-screws, and thus eliminates the necessity for plugs or the like. It will thus be seen that after the body is finished there is very little chance of checking or cracking 25 at the joint.

From the foregoing it is thought that the construction, operation, and many advantages of the herein-described invention will be apparent to those skilled in the art without further description, and it will be understood that various changes in the size, shape, proportion, and minor details of construction 30 may be resorted to without departing from the spirit or sacrificing any of the advantages 35 of the invention.

Having thus described my invention, what I claim as new, and desire to secure by Letters Patent, is—

1. In a vehicle-body, the combination with 40 a post, of angularly-disposed walls secured to the post and having their ends abutted to form a joint, and wire fabric fastened to both walls and bridging the joint between them, said fabric extending substantially the entire length 45 of the joint.

2. In a vehicle, a vehicle-body having a wall, said wall comprising an intermediate core-plate, paper sheathings secured to the inner and outer faces of the core-plate, and a metallic cap-strip covering the upper edges of 50 the core-plate and sheathings embracing the same and secured to the latter.

3. In a vehicle-body, a wall comprising a wooden core-plate, paper sheathings secured 55 to the inner and outer faces of the core-plate, and a metallic cap-strip covering the upper edges of the core-plate and sheathings, and having indented portions that engage with the sheathings and constituting fastening means 60 for the strip.

4. In a vehicle-body, the combination with a post, of a wall arranged against the post, fastening devices passing through the wall

and engaging the post, and a shield-plate secured to the exterior face of the wall and covering the fastening devices. 65

5. In a vehicle-body, the combination with a corner-post, of meeting walls arranged against the post and having cut-out portions in their outer faces, fastening devices passing 70 through the walls from the cut-out portions and engaging the post, and a corner-shield fitted in the cut-out portions and covering the outer ends of the fastening devices.

6. In a vehicle-body, the combination with 75 a post, of a wall having a portion resting against the post and comprising separate layers secured together, and a fastening device extending from one of the intermediate layers through the wall and engaging the post. 80

7. In a vehicle-body, the combination with a post, of a wall comprising a core, and an inner sheathing secured to the core and resting against the post, a fastening device passing through the wall and core and engaging the 85 post, and a shield secured to the outer side of the core and covering the fastening device.

8. In a vehicle-body, the combination with a post, of a wall comprising a core and an inner sheathing secured to the core and resting 90 against the post, an eyelet secured to the core, a fastening device passing through the eyelet and wall into the post, and a shield secured to the core and covering the fastening device and eyelet. 95

9. In a vehicle-body, the combination with a post, of a wall comprising a core and an intermediate sheathing secured to the core and resting against the post, fabric arranged 100 against the outer face of the core, a fastening device passing through the wall and engaging the post, and a shield covering the fabric and the fastening device.

10. In a vehicle-body, the combination with a corner-post, of angularly-disposed walls arranged against the post and comprising an inner sheathing, a core and an outer sheathing, said outer sheathing terminating short of the post, fastening devices passing through the core and inner sheathing and engaging the 105 post, and a corner-shield arranged over the fastening devices and filling the space left by the outer sheathing.

11. In a vehicle-body, a wall comprising a wooden core-plate, paper sheathings secured 110 to the inner and outer faces of the core-plate, and a metallic cap-strip covering the upper edges of the core-plate and sheathings, and secured to the sheathings only.

In testimony that I claim the foregoing as 115 my own I have hereto affixed my signature in the presence of two witnesses.

LOUIS PRIEST.
